UNITED STATES PATENT OFFICE.

EMIL A. HIRNER, OF ALLENTOWN, PENNSYLVANIA.

ART OF KNITTING SEAMLESS PLATED HOSIERY.

1,023,313.

Specification of Letters Patent.

Patented Apr. 16, 1912.

Application filed December 1, 1910. Serial No. 595,017

To all whom it may concern.

Be it known that I, EMIL A. HIRNER, of Allentown, in the county of Lehigh and State of Pennsylvania, have invented certain new and useful Improvements in the Art of Knitting Seamless Plated Hosiery, whereof the following is a specification, reference being had to the accompanying drawings.

10 The operation of plating is well known in knitting and consists in so feeding two threads simultaneously to the needles as to cause them to be knit together but in such a way that one thread, called the plating 15 yarn, always appears upon the face of the fabric, while the other, called the body yarn, always appears upon the back of the fabric.

16 In the knitting of seamless hosiery, no attempt has usually been made to plate the heel and toe pockets. The reason for this, is that these pockets are the result of a fashioning operation, in which the knitting is performed by a reciprocatory motion of the machine accompanied with narrowing and

25 widening of a flat web with interlooped selvages. The plating operation is a delicate one, its proper performance being dependent upon the relative positions and tensions of the threads as they enter the knitting operation. In the fashioning of a heel or toe pocket, the discovery of the proper position for the threads at the point where the sutures occur, *i. e.*, the union or interlooping of the selvages of the narrowed and 30 widened fabrics, has been a difficult problem and has not heretofore been solved. This has prevented the general adoption of plated stockings, for although the plating operation may be availed of in order to produce color effects in hosiery, yet one of its

35 important uses is to permit the lining of a stocking with an undyed or uncolored yarn. Many persons for sanitary reasons prefer to have the foot of a stocking made of such 40 undyed yarn, and, for this reason parti-colored stockings, sometimes called "split-foot stockings", are made with the leg and instep of colored yarn, and the sole and heel and toe pockets of undyed yarn. A much 45 neater and more serviceable stocking is one made throughout of colored yarn or silk, lined upon the inside with plain or undyed cotton yarn by a plating operation, and yet 50 the failure to successfully accomplish the 55 plating operation in the heel and toe pock-

ets, where its presence is most desired, has limited the field of the plated stocking.

According to my invention I am able to plate the entire seamless stocking so that, for instance, a colored yarn and an undyed 60 yarn may be used throughout, and throughout the stocking the colored yarn will appear on the outside and the undyed yarn on the inside. In speaking of a plated stocking, I do not necessarily include a ribbed 65 top, although, of course, this may be added and may also be plated if desired.

So far as concerns the parts of a seamless stocking which are knit in rotary fashion (that is to say, the entire leg and foot), no 70 description is here necessary, as they are composed of plain tubular rotary knitting, and are plated in the way which is known in the art. I will therefore confine my description to the special problem which I 75 have solved, to wit, the plating of the heel and toe pockets, and, as they are precisely alike, a description of one is a description of the other.

In the accompanying drawings, Figure I, 80 is a diagrammatic view of a stocking with a small square indicated therein in dotted lines to show the precise position of the portion of knitting illustrated in Fig. IV. Figs. II, and III, are enlarged views showing the position of the threads upon the needles respectively, immediately before and immediately after the reversal of the thread, in the formation of the suture loops. Fig. IV, shows upon an enlarged scale the structure 85 of a plated fabric when made in accordance with my invention, taken from the side of the heel pocket of the stocking illustrated in Fig. I, with the suture passing diagonally 90 across it.

95 Referring now to Fig. IV:—It will be observed that it consists of two knit selvaged fabrics with their courses at right angles and their selvages interlooped, and composed throughout of two yarns namely, a 100 plating yarn 1, indicated throughout by striated shading, and a body yarn 2, indicated throughout by absence of shading. The two yarns are knit together simultaneously throughout, but in such fashion as 105 to cause the plated yarn to always appear on the face of the fabric, and the body yarn upon the back. My invention relates to the method or process of knitting by which a selvaged fabric of this character is to be 110

produced. It will be convenient to first describe the fabric, and then refer more particularly to the method of knitting which I have discovered, and which results in the 5 successful production of such fabric.

Referring first to the parts of the fabric which are composed of plain knitting, it will be observed that the face of the knitting appears in the drawing. This presents the appearance of a succession of 10 double wales or ridges which consists of the diagonally arranged sides of the knitting loops. On the other hand, the back of the knitting (not visible) lacks this ridged appearance and consists entirely of the tops and bottoms of the loops; or, if we think of the succession of loops in a course of knitting, as corresponding to waves, the back of the fabric consists of the successive crests 15 and furrows. It will be seen that the loops do not lie lengthwise the fabric, but are almost horizontal, that is the ordinary knitting loop passes twice through the fabric its head and foot occupying the back and 20 its sides the face. The plating yarn at the back of the fabric lies within the circles constituting the tops and bottoms of the loops made by the body yarn, consequently, 25 the body yarn alone appears on the back and the plating yarn is here hidden, as for example, at 3, in Fig. IV. It must be borne in mind that the fabric is shown in a stretched condition so as to show as much, 30 as possible of the loops. When relaxed the walls formed by the sides of the loops are almost or quite in contact so that the tops and bottoms of the loops are not visible on the face of the fabric. At the sides of the loops the yarns come to the face after being 35 interlooped with the preceding course, and here the body yarn is buried in the fabric, while the plating yarn appears upon the face, as shown at 4. The description thus given applies to the entire two fabrics 40 shown, so far as they are composed of plain knitting. But these two fabrics have their courses at right angles to each other, and are finished by diagonal selvages each interknit with the other. This is the structure 45 which results from the fashioning operation as commonly practiced in the making of seamless hosiery, but it results in an irregularity in the knitting, and the problem which I have solved has been the discovery 50 of the method of laying the two threads during the interknitting of these selvages for the production of a suture, by which the same effect is produced throughout, to wit, the plating yarn maintained constantly 55 on the face of the fabric and the body yarn on the back, so that the suture is plated as well as the ordinary straight courses of the narrowed and widened fabric. This plating of the suture is most important not 60 only because of the improved appearance of

the product, where the suture portions are plated, but because if there is here a reversal of the yarns, it perpetuates itself in the straight courses of the heel or toe producing a mottled result.

The selvage formation which is illustrated, is that most commonly used in American seamless hosiery, in which the narrowing and widening process is performed upon what is known as the two and one method, a method well known to those skilled in the art and which need not be here described, but it is obvious that my invention is equally applicable to a selvage formed upon the one and one method.

Referring to the selvage of that fabric shown in the drawings, in which the courses run horizontally, the yarns for each course are numbered from 10 to 20, and being laid in a reciprocating fashion, the even numbers 85 must be considered as running one way and the odd numbers running the other. It will be sufficient to describe the selvage of two courses, as all the others are identical. Taking for example, the course numbered 18, it 90 is cut off at the top of a loop. After making the complete loop the top of which is numbered 21, it passes down at 22, up at 23, and then instead of forming an ordinary loop, forms the selvage loop 24, in which as before the plating yarn is maintained upon the inside of the loop, so that the body yarn is thrown to the back. With the yarns in this position the side of the selvage loop is retracted behind the bottom of the loop 95 which immediately preceded the selvage loop re-appearing at 25. During this distance the body yarn has been maintained at the back, so that it maintains its position where the thread again interloops with the right 100 hand side of the loop whose top is marked 21, after which it reappears upon the face of the fabric at 26, and 27, which are the sides of the loops of a new course 19. It will be observed that the plating yarn which 105 has been buried in the fabric since the formation of the selvage loop 24, here properly reappears upon the face at the sides of the loops and continues in this position during the entire course 19. Coming now to the 110 other fabric formed of vertical courses, which are numbered from 30 to 42, it will be convenient to take the thread which is numbered 38, and follow its course as indicating the course of all the other evenly numbered threads. It forms a loop the top of which is marked 44, with the plating yarn held to the inside of the half circle formed by the body 115 yarn which is there thrown to the back of the fabric. Where the head of the next loop should be formed, the yarns at 45, are both temporarily buried in the fabric, and then pass to the back as indicated by the dotted lines 46, the body yarn here lying upon the 120 back. The yarns continue and completely 125

encircle the sides of the selvage loop of the other fabric, which is formed by the yarn 16, and come to the face of the fabric at 47, with the plating yarn forming the sides of a loop lying to the face. This loop just described constitutes the selvage loop of this course, that is to say, it is the point where the yarns after passing in one direction retrace their steps and are laid in the other direction. 5
 10 This loop is completed at 49, after which the threads pass to the back after having interlooped with the bottom of the loops formed by the yarn 16, and pass diagonally at 50, where the body yarn is visible upon 15 the back and are retracted to form the loops, of which the sides are marked at 51, and 52. At 53, these yarns are again at the back of the fabric with the body yarn there showing, from whence their course to 39, is readily 20 traced.

The fabric which I have thus described, is 17 I believe new, considered as a structure. Its characteristic is that in the formation of the selvage loop; and during the entire irregular course which the yarns are required to 25 follow in order that they may take their place in the formation of the next course, (that is throughout the entire suture portion), the special positions of the two yarns 30 are maintained, that is to say, the plating yarn invariably takes the short course in the rounding of the head or foot of the loop, so that the body yarn there appears upon the back of the fabric, while on the other hand, 35 at the sides of the loops the plating yarn overlies the body yarn on the face of the fabric. I have discovered that in order to produce a fabric of this character, in which a 40 fashioning suture is incorporated in the knitting and plated, it is essential that the two yarns shall be fed to the needles in a definite and predetermined way, and especially that this position of the yarns be maintained with great accuracy at a certain 45 critical point of the operation, to wit:—the point where the return of the threads occurs in the formation of the suture. The importance of properly feeding the two threads to 50 the needles at this point of the operation rests in the fact that if inversion of the threads occurs at this point, it perpetuates itself during the entire course of knitting which succeeds, thereby ruining the plated effect. The method of knitting which I employ, and which results in the fabric which I 55 have described, will be understood by reference to Figs. II, and III, of the drawings.

Fig. II, represents three successive needles 60, 61, and 62. The plating thread and the body thread are indicated at 1, and 2, respectively. As shown in Fig. II, 61, is the last needle of the fashioning set for the course which is being knit, while 60, is the end needle of the idle set holding a loop of the preceding course. The two threads 1, and 2,

have been fed within the hooks of needles 62, and 61, so that the body yarn 2, lies uppermost upon the shank of the needle, while the plating yarn being fed at a more obtuse or flat angle lies below, the result being the formation of a knit fabric in which the body yarn shows upon the back and the plating yarn upon the face of the fabric. At the point in the knitting operation illustrated in Fig. II, the yarn carrier is carrying the two 70 yarns beyond the end of the fashioning set without continuation of the knitting operation, because of the fact that the needles from 60, on, are raised to the idle level and cannot knit. Soon the yarn carriers return 75 upon themselves occasioning, as this operation is usually performed, a slackening of the tension. It is here that the natural twist of the yarns entangling the fuzz which ordinarily projects from knitting yarns, tends to 80 occasion a reversal of the position of the threads. This I avoid by properly controlling the position of the threads as the yarn carrier passes to the other side of the first needle of the fashioning set, as shown in 85 Fig. III, so that the threads are in their proper relative positions prior to the feeding of the thread to the first and succeeding needles of this active series. It will be observed in the figure, that this needle has advanced sufficiently to take the threads under 90 its hook, and it must be especially observed that in this reversed position, the body thread is again fed across the shank of the needle over the plating thread. This is accomplished by reversing the plating yarn under tension, to a symmetrical position similar to that which it occupied when moving in its first direction, and at a similar obtuse angle. The body yarn is likewise reversed at 95 its prior angle, both threads being thus correctly positioned on the first and succeeding needles of the active series. By laying the threads in this fashion, at this critical point, 100 inversion of the threads is prevented, and a continuation of the plating process course by course, is insured.

The machine which I have devised to enable me to most conveniently carry out the process herein claimed, is described in an application filed by me under date of February 15th, 1907, Serial Number 357,462.

I am aware of efforts which have previously been made, although as far as I can discover, always unsuccessful, to plate the straight courses of narrowed and widened fabric, which make up heel or toe pockets. The lack of success of such efforts has been due, as I believe, to the failure of the knitter to realize how to plate the suture with regard to the structure formed by the interlooped selvage loops, and the yarns by which they are connected. By devising the system of plating which I have described, I have 115 solved the problem of plating a suture, in 120 125 130

cluding all the selvage loops of the structure, and I find that by doing this, the difficulties which have heretofore been found in the plating of the heel and toe members of a 5 stocking, are done away with; since if once the suture loops are plated according to my scheme, the maintenance of the proper position of the threads throughout the straight courses presents no particular difficulty, 10 while on the other hand, if, as has heretofore been the case, no regard is had to specially plating the suture, and the yarns are allowed to lie in haphazard relation during this part of the knitting, it is practically impossible 15 to maintain the proper position of the yarns during the straight courses of the narrowed and widened fabric, since if the yarns start from the suture in a reversed position the reversal tends to perpetuate itself. 20 Having thus described my invention, I claim:—

The improvement in the art of knitting seamless plated hosiery, which consists in feeding simultaneously to the active needles, 25 body thread and plating thread in different

angular relation, with the body thread uppermost on the shank of the needle, and the plating thread occupying the flatter angle; continuing this operation to the point where the threads turn upon themselves to form the 30 suture loops of the fashioned portion; and thereupon as the direction of the travel of the threads is reversed, throwing the plating thread to a reversed position at a similar flat angle, and throwing the body thread 35 over the plating thread at a higher angle prior to the feeding of the thread to the first and succeeding needles of the active series, whereby the proper relation of the threads is maintained during the loops immediately succeeding reversal, and throughout the knitting operation.

In testimony whereof, I have hereunto signed my name at Allentown, Pa., this twenty-fifth day of November, 1910.

EMIL A. HIRNER.
